(57) **CLAIM**

The ornamental design for a headgear for a nasal mask, as
shown and described.

DESCRIPTION

FIG. 1 is a top, front and side perspective view of a headgear
for a nasal mask showing our new design, the headgear
shown in an in-use configuration to wrap around a user's
head.

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 shows an enlarged detail line drawing of a knitted
surface texture.

The hatched areas of the straps of the headgear in FIGS. 1-7
shall be comprised of the knitted surface texture as shown in
FIG. 8.

The dash-dot broken lines in FIGS. 4 and 8 define the
bounds of the enlargement and form no part of the claimed
design.
